US00D510535S

(12) **United States Design Patent** (10) Patent No.: **US D510,535 S**
Sandell (45) Date of Patent: **** Oct. 11, 2005**

(54) **MOTION DETECTOR HEAD**

(75) Inventor: **Donald R. Sandell**, San Jose, CA (US)

(73) Assignee: **EML Technologies LLC**, Danville, CA (US)

(**) Term: **14 Years**

(21) Appl. No.: **29/198,139**

(22) Filed: **Jan. 24, 2004**

(51) **LOC (8) Cl. 10-05**

(52) **U.S. Cl. D10/104**

(58) **Field of Search** D10/156, 104, D10/116, 121; D14/426, 299, 358, 432; D13/123; 340/521, 555, 556, 557, 600

(57) **CLAIM**

The ornamental design for a motion detector head, as shown and described.

DESCRIPTION

FIG. 1 is a perspective view of a motion detector head showing my new design;

FIG. 2 is a right elevational view of the motion detector head of FIG. 1; the left elevational view is a mirror image;

FIG. 3 is a top plan view thereof;

FIG. 4 is a front elevational view thereof;

FIG. 5 is a rear elevational view thereof; and,

FIG. 6 is a bottom plan view thereof, with the broken line shown for illustrative purposes only and forming no part of the claimed design.

1 Claim, 2 Drawing Sheets
